CLAIM

The ornamental design for an artificial stone wall, as shown and described.

DESCRIPTION

The design consists of the features of shape, ornamentation and configuration of the artificial stone wall shown in the drawings.

FIG. 1 is a perspective view of the stone wall;

FIG. 2 is a top view thereof;

FIG. 3 is a front view thereof;

FIG. 4 is a bottom view thereof;

FIG. 5 is a rear view thereof;

FIG. 6 is a right-hand side view thereof; and,

FIG. 7 is a left-hand side view thereof.
